(57) **CLAIM**

The ornamental design for a bartop gaming console as shown and described herein.

DESCRIPTION

FIG. 1 is a top view of a bartop gaming console of one embodiment of our new design.

FIG. 2 is a front view of the bartop gaming console of FIG. 1.

FIG. 3 is a left side view of the bartop gaming console of FIG. 1.

FIG. 4 is a right side view the bartop gaming console of FIG. 1.

FIG. 5 is a rear view of the bartop gaming console of FIG. 1.

FIG. 6 is a bottom view of the bartop gaming console of FIG. 1.

FIG. 7 is a front perspective view of the bartop gaming console of FIG. 1.

FIG. 8 is a rear perspective view of the bartop gaming console of FIG. 1.

FIG. 9 is a top view of a bartop gaming console of another embodiment of our new design.

FIG. 10 is a front view of the bartop gaming console of FIG. 9.

FIG. 11 is a left side view of the bartop gaming console of FIG. 9.

FIG. 12 is a right side view the bartop gaming console of FIG. 9.

FIG. 13 is a rear view of the bartop gaming console of FIG. 9.

FIG. 14 is a bottom view of the bartop gaming console of FIG. 9.

FIG. 15 is a front perspective view of the bartop gaming console of FIG. 9; and,

FIG. 16 is a rear perspective view of the bartop gaming console of FIG. 9.

(Continued)

The broken lines are for the purpose of illustrating portions of the article that forms no part of the claimed design.

1 Claim, 16 Drawing Sheets

Related U.S. Application Data

a continuation of application No. 29/868,069, filed on Nov. 18, 2022, now Pat. No. Des. 998,048, which is a division of application No. 29/673,196, filed on Dec. 12, 2018, now Pat. No. Des. 973,773.

(58) Field of Classification Search

CPC A63F 9/00; A63F 9/24
See application file for complete search history.
